FURNACE

Elwood S. Burch, Dowagiac, Mich., assignor to
 Round Oak Furnace Company, Dowagiac,
 Mich., a corporation of Michigan

Application August 8, 1935, Serial No. 35,380

5 Claims. (Cl. 126—242)

The present invention relates to improvements in furnaces, more particularly to warm air heating furnaces of the type employed to heat air to be supplied to the rooms of a dwelling or the like, although not limited to this type of furnace.

Heretofore, in arranging the fuel for efficient operation in the firepot of a furnace or heating apparatus of the character indicated, it frequently became necessary to remove hot smoking clinkers therefrom in order to bring the fire in the firepot to a satisfactory condition. This was usually accomplished by removing the clinkers from the firepot, followed by placing same in an open receptacle or on the basement floor, with the attendant emission from the clinkers of offensive, odorous gases, smoke and dust, all of which filled the aforementioned basement. This not only littered up the furnace room, but proved to be injurious to the health 20 of the furnace attendant and generally not conducive to a clean and efficient operation of the furnace.

One of the primary objects of the present invention, therefore, is to provide means forming an integral part of the furnace for receiving the clinkers removed from the firepot so that the smoke, odorous gases and dust do not enter the furnace room.

Still a further purpose is to construct a furnace having a receptacle to specially receive the clinkers removed from the firepot of said furnace.

Yet a further aim is to provide a furnace having a receptacle for receiving hot clinkers, so arranged that the gases, smoke and dust rising therefrom will pass off through the flue of the furnace without any leakage into the building in which the furnace is located.

Another object of the invention is to provide a furnace with a housing, the latter characterized by a chute and clinker-receiving receptacle, whereby there results a clean, convenient and healthful means of removing and disposing of hot clinkers.

The above and other aims and purposes will be apparent from the detailed description hereinafter appearing, when read in conjunction with the accompanying drawings showing one embodiment of the invention, and in which,

Figure 1 is a perspective view of a hot air furnace showing the invention applied thereto and with the fuel-feeding door and the door for the receptacle-holding portion of the casing of the invention in open position.

Figure 2 is a perspective view of the housing or casing of the invention prior to attachment

thereof to the furnace, with the doors eliminated and with the receptacle removed from the receptacle-holding chamber.

Figure 3 is a sectional view taken on line 3—3 of Figure 1.

Referring for a moment to Figure 1, there is shown a furnace, designated generally as F, and including a combustion chamber 5 having a dome-head 6, stoker extension 7, right side radiator 8 connected to chamber 5 by extension 9, 10 and left side radiator 10 secured to the chamber by extension 11. Up to the present the structure described is more or less conventional and forms no part of the novel improvement. Attached forwardly of the furnace, that is to that portion 15 thereof normally having a fuel-feeding and clinker-removal opening, is a housing or casing 15 which is preferably arc-welded to the combustion chamber 5. By reference to Figures 2 and 3 it will be noted that the casing 15 is composed of 20 an upper section 16 connected by a chute 17 to a bottom or lower section 18, the latter adapted to receive a receptacle 19. The section 16 is a box-like structure having a top 20 and opposed side walls 21 and 22, while the bottom wall 23 has 25 an opening 24 substantially centrally thereof, leading to the chute 17. The latter constitutes a conduit leading to the lower section 18 which has side walls 25 and 26 and a lower wall or bottom 27 and a rear wall 27a. From the above 30 description it will be apparent that the section 16 is open at its rear and that this section is in alignment with the fuel-feeding opening of the furnace F. Covering the front of upper section 16 is a front wall member 29 which may be permanently connected thereto as by riveting, arc-welding or the like. The wall 29 is provided with an opening 30 closed by hinged door 31. Similarly the front of the lower section 18 is equipped 35 with a front wall 32 having an opening normally 40 closed by a hinged door 33. Walls 29 and 32 have aprons which meet in an overlap 32'. As indicated, receptacle 19 is open at its top, rests on the bottom wall 27 of the section 18 and is capable of being drawn forwardly through the opening closed by door 33, by means of a handle 34 or the like pivoted on the receptacle.

In the use of the invention and when it is desired to improve the condition of the fire bed in the furnace, the door 31 is swung to open position 50 and the bed reached in the usual manner. Clinkers may be raked or lifted forwardly into the section 16 and then dropped through chute 17 into clinker receptacle 19. During this operation door 33 will remain closed, and after the 55

clinkers have been removed door 31 may also be closed, which will permit the smoke, odorous gases and dust from the clinkers to pass off through the flue of the furnace. Then may follow the addition of fuel to the fire bed through the opening closed by door 31. After the clinker-receiving receptacle 19 has become filled, door 33 is opened, the clinkers emptied from the receptacle and the latter replaced in position for further use.

From the above description it will be apparent that there has been provided novel means well adapted to permit the removal of clinkers from the firepot of a furnace without the usual inconveniences normally attending this operation. Although a preferred embodiment of the invention has been shown and described, it will be appreciated that numerous changes and variations may be made in structural details, and it is my intention to cover all such and to be limited in this respect only as may be necessary by the scope of the claims hereto appended.

I claim:

1. In a furnace, a combustion chamber having a fuel-feeding and clinker-removal opening, a housing secured to said chamber in direct communication with said opening, and removable means within said housing for receiving clinkers removed from said chamber through said opening, said housing including means for guiding the clinkers to said removable means.

2. In a furnace, a combustion chamber having

a fuel-feeding and clinker-removal opening, a housing secured to said chamber in direct communication with said opening, a receptacle within said housing, the latter including means for directing clinkers removed from said chamber through said opening to said receptacle.

3. In a furnace, a combustion chamber having a fuel-receiving and clinker-removal opening, a housing secured to said chamber in direct communication with said opening, said housing having upper and lower sections and a chute connecting same, and a receptacle in the lower section beneath the chute.

4. In a furnace, a combustion chamber having a fuel-receiving and clinker-removal opening, a housing secured to said chamber, said housing having upper and lower sections and a chute connecting same, the upper section open at its rear and said open portion being aligned with said opening.

5. An attachment for furnaces and the like having a combustion chamber and a fuel-receiving and clinker-removal opening, said attachment comprising a housing adapted to be secured to the forward portion of the chamber, the housing including an upper section in direct communication with said opening, a lower section, and a chute connecting said sections, a receptacle in said lower section, each of said sections being open at the front, and a door for each of said last-mentioned openings.

ELWOOD S. BURCH.
